UNITED STATES PATENT OFFICE.

WALTER L. KEEFER, OF FITCHBURG, MASSACHUSETTS.

ADJUSTABLE EXPANDING CENTER.

1,219,744.

Specification of Letters Patent. Patented Mar. 20, 1917.

Application filed April 27, 1916. Serial No. 3,927.

To all whom it may concern:

Be it known that I, WALTER L. KEEFER, a citizen of the United States, residing at Fitchburg, in the county of Worcester and State of Massachusetts, have invented certain new and useful Improvements in Adjustable Expanding Centers; and I do declare the following to be a full, clear, and exact description of the invention, such as will enable others skilled in the art to which it appertains to make and use the same.

This invention relates to tools used by machinists and other workmen for determining the centers of the circular recesses, openings, or bores through metal castings, or other objects.

The primary object of the invention is to overcome the heretofore waste of time in determining in a very inaccurate way the exact center of such an opening or bore in a casting, by the provision of an adjustable expanding tool or center, the centering pin of which is designed to be normally centrally arranged with respect to a plurality of arms adapted to engage the interior sides of the opening or bore in the casting. The point so determined may be used as the center of a circle to be scribed on the casting concentric to the opening or bore therein, or to be used as a fixed point from which to take measurements of any desired nature.

A further object of the invention is to provide a device of this character wherein the centering pin is adjustably mounted with respect to the central axis of the device in order that it may be moved out of its normal position so that a circle may be scribed or measurements taken from a point eccentric to the longitudinal axis of the opening or bore in the casting.

A still further object of the invention is to provide a device of this character which will be of simple, comparatively strong, durable and inexpensive construction, efficient and reliable in operation, and well adapted to the purpose for which it is designed.

With these and other objects in view, the invention consists of certain novel features of construction, and the combination and arrangement of parts as will be hereinafter fully described and claimed.

The accompanying drawings, forming part of the specification, illustrate one way in which the invention may be constructed, and wherein:

Figure 1 is a top plan view of a device

constructed in accordance with this invention;

Fig. 2 is a side elevation of the same showing the application thereof to the bore or recess in a metal casting;

Fig. 3 is a sectional view taken on the plane of the line 3—3 of Fig. 1;

Fig. 4 is a top plan view of the device with the top plate removed;

Fig. 5 is a similar view of the device with the casing removed from the base member showing the concentrically mounted cam carrying plate;

Fig. 6 is a similar view of the central portion of the device showing the centering pin in a position eccentric to the longitudinal axis of the device;

Fig. 7 is a perspective view of the disassembled elements forming the centering pin; and,

Fig. 8 is a similar view of the locking dog and handle member therefor.

Similar reference characters designate like parts throughout the several views.

Referring more particularly to the drawings, the reference numeral 1 designates a circular or cylindrical casing having a centrally arranged circular opening 2 in its closed end, the other end being open, and a plurality of notches 3 in its sides. Secured to the open end of the casing 1 by suitable screws 4 is a base member, here shown in the form of a circular plate 5.

This plate 5 is provided with a centrally arranged opening 6, from which radiates a plurality of rectangular channels 7. These channels 7 have their outer ends disposed in alignment with the aforesaid notches 3, and have slidably mounted therein a plurality of 95 radially extending arms 8, the purpose of which will be hereinafter described.

The reference numeral 9 designates a circular member or plate having a centrally arranged aperture 10 therein through which extends a shaft 11, the inner end of which is provided with a head 12. This plate 9 is revolvably mounted concentrically with respect to the aforesaid plate 5, and is provided with a plurality of cams, here shown 105 in the form of scroll devices or slots 13, that is, arcuate slots extending spirally from the central axis of the plate. Extending laterally from the inner sides of the arms 8 at the inner ends thereof are suitable pins 14, said pins being received in the scroll slots 13, whereupon when the plate 9 is revolved, the

arms 8 will be moved outwardly or inwardly according to the direction in which the plate 9 is turned, the outer ends of said arms always moving concentrically relatively to the central axis of these plates.

The plate 9 is provided on its inner side with a suitable catch in the form of a radially slidable dog 15, the latter being provided with a pair of spaced arms 16 at its inner end which straddle the head 12 of the shaft 11, while the outer end of the dog 15 is bent laterally at right angles and twisted for a purpose to be described. Extending laterally from the plate 9 is a pair of spaced stops or pins 17, between which the outer end of the dog 15 is disposed, thereby preventing the latter from swinging around the head 12. Fixed at one end to one of the pins 17 is an arcuate resilient spring 18, the other end of which is hooked around or otherwise secured to the outer end of the dog 15. It is to be understood that by this construction, the dog 15 is normally forced outwardly into engagement with suitable ratchet teeth 19 arranged on the inner side of the casing 1. These teeth are here shown formed on the outer edge of an arcuate slot 20 arranged in the end of the casing. The laterally bent outer end of the dog 15 extends through this arcuate slot 20, and comprises, in effect, a thumb piece or handle 21 to be engaged when it is desired to operate the dog and move the plate 9 within the casing 1.

Extending through the opening 2 of the casing is a centering member in the form of a pin 22, the inner end of which is provided with a disk-like head 23 between which and the inner side of the end of the casing is disposed a spring washer 24. This head 23 under the tension of the washer 24 bears firmly against the head 12 of the aforementioned shaft 11, thus yieldably clamping said centering pin in place so as to allow the same to be positioned either concentric or eccentric to the central axis of the casing. The free end of the pin 22 is provided with a small centrally arranged recess 25 which is adapted to receive the pivot point of a compass when it is being used as a center when scribing a circle around the opening in a casting, or when it is being used as a point from which measurements may be taken, the purposes of which will be apparent to those skilled in the art.

Secured by suitable screws 26 to the end of the casing 1 is a circular plate 27, the latter having a centrally arranged opening 28 and an arcuate slot 29 disposed respectively in alignment with the aforesaid opening 2 and slot 20 in the casing. Extending outwardly from the edges of this plate 27 are fingers 30, the outer ends of which are disposed in planes beyond the outer limit of the arms 8, for a purpose to be described.

The device is shown in Figs. 2 and 3 of the drawings as being applied to a conventional metal casting B having an opening or bore A extending therethrough, the fingers 30 contacting with the end of the casting 70 and preventing the entire device from being inserted too far into the opening while the arms 8 are engaged at their outer ends with the sides of the bore. It is of course to be understood that these arms 8 are moved or brought into firm contact with the bore by turning the plate 9 in the manner hereinbefore described. The dog 15, under the tension of its spring, engages the teeth 19 and normally retains the arms in their extended 80 positions, and thus locks the device in place.

The device being thus locked in the bore, and it is known that the centering pin 22 is positioned in the exact center of the device, said pin will coincide with the exact 85 center of the bore, and measurements may be taken from the point or recess 25 thereof, or circles may be scribed therefrom concentric to the bore of the casting. If, however, it is desired to scribe circles from a point 90 eccentric to the central axis of the bore, it is only necessary to move the centering pin 22 out of its known centered position. This may be readily done in the hereinbefore described manner, owing to the fact that it is 95 adjustably mounted with respect to the shaft 11. The spring washer 24 is always under sufficient tension to cause the head 23 of the pin to firmly engage the head 12 of the shaft 11 and prevent accidental displacement of 100 the pin.

The pin 22 may be approximately centered by eye-sight, as even a very small amount of eccentricity between the pin and the opening 2 will be noticeable. However, 105 this can be accurately determined by scribing on the end of the casting at 90 degrees apart, four arcs of a circle of a greater radius than the bore of the latter. These arcs should be equi-distant from the bore of the 110 casting. If they are not, then the pin is eccentrically positioned, the amount of such eccentricity being numerically equal to one-half the difference between the distances of two diametrically opposite arcs from the 115 bore. When this has been determined, the pin may be moved in the proper direction this amount. It is then centered in the same manner with respect to the other two diametrically opposite arcs.

By taking similar measurements with a compass or pair of dividers, the pin may be moved eccentrically the exact amount, it of course being primarily in its central position.

From the foregoing description, taken in connection with the accompanying drawings, the construction and advantages of the invention will be understood without a more extended explanation.

As various changes in form, proportion, and in the minor details of construction may be resorted to without departing from the spirit of the invention, I do not wish to be limited to the construction herein shown and described, other than that set forth in the appended claims.

I claim as my invention:

1. A device of the class described comprising a casing, a plurality of arms extending from said casing, a member revolvably mounted within said casing and provided with means for moving said arms concentrically to the central axis of the same, a dog slidably mounted on said member, a spring fixedly mounted within said casing and operatively connected with said dog for forcing the latter outwardly, and ratchet teeth arranged on the inner side of said casing and engaged by said dog for locking said member against movement.
2. A device of the class described comprising a casing, a plurality of arms extending from said casing, a member revolvably mounted within said casing and provided with means for moving said arms concentrically to the central axis of the same, a dog radially slidable on said member, a spring fixedly mounted within said casing and operatively connected with said dog for forcing the latter outwardly, ratchet teeth arranged on the inner side of said casing and engaged by said dog for locking said member against movement, said casing being provided with an arcuate slot in one of its ends, and a handle extending laterally

from the outer end of said dog for operating the same and for revolving said member within said casing.

3. A device of the class described comprising a casing, a plurality of arms projecting from said casing, means mounted within said casing for moving said arms radially and holding them concentric to the central axis of the same, and a centering member adjustably mounted within said casing with respect to the central axis thereof and having means for frictionally holding it in its adjusted position.

4. A device of the class described comprising a casing having a central opening at one end thereof, a plurality of arms projecting radially from said casing, means mounted within said casing for moving said arms radially and holding them concentric to the central axis of the same, a centering pin extending longitudinally with respect to said casing, the inner end of said pin being disposed within the latter, the outer end of said pin extending through said opening to the exterior of said casing, and a head carried by the inner end of said pin yieldably clamped within said casing to allow said pin to be moved eccentrically with respect to the central axis of the same.

In testimony whereof I have hereunto set my hand in presence of two subscribing witnesses.

WALTER L. KEEFER.
